A. J. CARVER ET AL

BURGLAR ALARM

Filed Apr. 27, 1921

UNITED STATES PATENT OFFICE.

ANDREW J. CARVER AND JES T. BEASLEY, OF OBION, TENNESSEE.

BURGLAR ALARM.

Application filed April 27, 1921. Serial No. 465,072.

To all whom it may concern:-

Be it known that we, ANDREW J. CARVER and JES T. BEASLEY, citizens of the United States, residing at Obion, in the county of Obion and State of Tennessee, have invented 5 certain new and useful Improvements in Burglar Alarms, of which the following is a specification.

The object of this invention is to provide 10 simple and efficient means which may be readily applied to a door or window so that upon unauthorized opening of the closure an alarm will be sounded to notify the occupants of the room or the building of the 15 intrusion. A further object of the invention is to provide a device for the stated purpose which may be readily set in position to permit free opening and closing of the door or window during the day or at 20 such times when the entrance of persons will be readily noted and which may be as readily set to sound the alarm at night or at other times, and a still further object of the invention is to provide a device which will 25 not detract from the appearance of the door and which may be installed at a very low cost.

The invention is illustrated in the accompanying drawings, in which—

30 Figure 1 is a front elevation of a door having our improved alarm applied thereto;

Figs. 2 and 3 are edge views showing different positions of the alarm.

In the drawings, the reference numeral 1 35 indicates a door of any desired or well-known construction and 2 indicates the door frame in which the door is mounted. In carrying out our invention, as illustrated, we mount a rock shaft 3 in suitable bearings 4 upon the door frame above the door and this rock shaft is provided at its ends with normally depending crank arms 5 and 6 and at an intermediate point with a crank arm 7 which normally projects forward 40 from the door frame. The crank 5 is constructed with an eye 8 at its extremity in which is engaged the upper end of a setting rod 9 and the lower end of the said rod is formed into a hook 10 adapted to engage an eye or other form of retainer 10' on the door frame. The crank 7 is in the form of an arch or bail and between the sides thereof we set in the door frame a push button or circuit closer 11, the said button or circuit closer being connected with a bell or other alarm 12 through an electric circuit,

as indicated conventionally in Fig. 1. It will be readily understood that the bell or alarm may be located at any desired or convenient point in the room or building so 60 that, when the circuit is closed, an alarm will be sounded at a point where it is most apt to be clearly heard. A presser in the form of a leaf spring 13 is secured at its upper end on the door frame above the 65 shaft 3 and has its free end constantly bearing upon the end of the crank or bail 7.

It is thought the operation of the device will be readily understood. When the device is set for operation, the crank 6 will depend over the upper end of the door, as clearly shown in Fig. 1, and the crank or bail 7 will extend over and across the circuit closer 11 with the end of the presser 13 bearing upon the end of the said crank. 75 The setting rod 9 will be released from the retainer 10' so that its lower end will be free and will not interfere with the rotation or rocking of the shaft 3. When thus arranged, opening of the door will cause the 80 door to ride against the crank 6 and swing the same upwardly thereby rocking the shaft 3 and, of course, causing the crank 7 to turn upwardly from over the circuit closer. As soon as the crank 7 has cleared 85 the dead center, the resiliency of the spring 13 will act upon the said crank so as to swing it close to the door frame, as shown in Fig. 3, and the free end of the spring will be thereby permitted to strike upon the projecting movable member of the circuit closer 90 and force the same inwardly so as to close the circuit and sound the alarm in an obvious manner. If it be desired to permit free opening and closing of the door without 95 sounding the alarm, the end of the setting rod 9 is engaged in the retainer 10 and the rocking of the shaft 3 will be thereby limited. When the setting rod is thus restrained, as shown in Fig. 1, opening of the 100 door will actuate the crank 6, as previously described, but the shaft 3 will be limited in its movement so that the crank 7 cannot swing close to the door frame and the presser 13 will be prevented from coming into 105 contact with the movable member of the circuit closer and will be held in an inoperative position, as shown in Fig. 2. The door may then be freely opened or closed without actuating the rock shaft, as will be readily 110 understood.

It will be readily noted that our device is

exceedingly simple in the construction and arrangement of its parts and may be readily applied to any door at a very low cost. When set for use, it will operate efficiently and an alarm will positively be given when the door is opened.

Having thus described the invention, what is claimed as new is:

1. A burglar alarm comprising a rock shaft, a crank projecting from the rock shaft adapted to be interposed into the path of a moving member, a second crank extending from the rock shaft at an angle to the first-mentioned crank, a circuit closer arranged below said second crank, and a presser member bearing constantly upon said second crank and arranged to actuate the circuit closer when the first-mentioned crank is actuated by the moving member.
2. A burglar alarm comprising a rock shaft to be mounted adjacent a closure, a crank depending from said shaft into the path of the closure, a circuit closer mounted in the plane of the shaft, an arched crank in the shaft normally extending over said

circuit closer, and a yieldable presser bearing constantly upon said arched crank and normally held thereby away from the circuit closer and adapted to actuate said circuit closer when said crank is moved beyond 50 the circuit closer.

3. A burglar alarm comprising a rock shaft having an arched crank portion, a crank depending from said shaft into the path of a swinging member, a setting crank 55 on the rock shaft, a setting rod engaged in said setting crank, a retaining device to be engaged by said setting rod, a circuit closer disposed under the arched crank, and a leaf spring secured at one side of and extending 60 across the rock shaft to bear constantly upon the arched crank portion and be thereby held normally away from the circuit closer but adapted to actuate the circuit closer when said arched crank portion is moved to 65 a position around the circuit closer.

In testimony whereof we affix our signatures.

ANDREW J. CARVER. [L.S.]
JES T. BEASLEY. [L.S.]
